UNITED STATES PATENT OFFICE.

JOHN F. LEVAN, OF ELKHART, INDIANA, ASSIGNOR, BY MESNE ASSIGNMENTS, TO THE ADAMS & WESTLAKE COMPANY, OF CHICAGO, ILLINOIS, A CORPORATION OF ILLINOIS.

SASH CONSTRUCTION.

Application filed May 22, 1926. Serial No. 110,894.

The present invention has to do with sheet metal sash, and is particularly concerned with the construction of the marginal stile and rail members.

5 The principal object of the invention is to provide, in a sheet metal sash, an improved marginal member which is light, strong, narrow and extremely economical to manufacture.

10 Another important object is to provide an improved lock which is especially suitable for association with such a marginal member.

15 While the foregoing statements are indicative in a general way of the nature of the invention, other objects and advantages not herein specifically mentioned will be apparent to those skilled in the art upon a full comprehension of the improved sash construction.

20 In order that the invention may be readily understood, one embodiment of the same is presented in the accompanying drawings and in the following description, but it will be understood that such embodiment is intended merely for the purpose of exemplification and is not to be considered as limiting the invention short of its true and intended scope, as defined by the appended 25 claims.

In the drawings—

Fig. 1 is a fragmentary side view of a sash which is constructed in accordance with the invention;

35 Fig. 2 is a horizontal section through the sash, taken on the line 2—2 of Fig. 1;

Fig. 3 is a vertical section, taken on the line 3—3 of Fig. 2;

40 Fig. 4 is a vertical section, taken on the line 4—4 of Fig. 2;

Fig. 5 is a vertical section, taken on the line 5—5 of Fig. 1;

Fig. 6 is a vertical section, taken on the line 6—6 of Fig. 4;

45 Fig. 7 is a horizontal section, taken on the line 7—7 of Fig. 1; and

Fig. 8 is a fragmentary perspective view of one of the stile members of the sash.

The marginal stile and rail members 10 and 11 of the sash illustrated in the drawings are of hollow sheet metal formation. Each of the marginal members consists of two U-shaped channel strips 12 and 13 which are arranged together in nested relation, with

the edges 14 of the inner strip 13 bent 55 reversely about and secured to the edges of the outer strip 12, and with the back 15 of the inner strip spaced a substantial distance from the back 16 of the outer strip. The channel in the inner strip 13 constitutes 60 a groove for the reception of the usual glazing strip 17 and pane 18, while the channel in the outer strip 12, which is relatively deep, is closed off by the back 15 of the inner strip and that part of it not occupied 65 by the inner strip constitutes a space for the reception of such hereinafter described elements as the corner reinforcing members between the stile and rail members and the bolts of the locks associated with the sash. 70

Two locks are advantageously applied to the two lower corners of the sash. Each of the locks includes an L-shaped housing 19, which opens against the sash and spans the joint therein between one of the side stile 75 members 10 and the bottom rail member 11. The housing 19 is provided along its upper edge with a stationary lift piece 20. A movable finger piece 21 is positioned at an inclination above and to the side of the lift piece 20, and is pivoted at 22 within the housing 19. A spring 23 is secured within the housing at one side of the finger piece 21, and bears resiliently against a shoulder 24 on the same, whereby to hold the finger 80 piece normally in spaced relation to the lift piece 20. The finger piece 21 is provided, intermediate the pivoted and free ends thereof, with a laterally projecting pin 25 which extends through an opening 26 in one of the 85 sides of the channel strip 12 of the lower rail 11, and engages against the sides of a slot 27 in a bolt 28.

The bolt 28 is positioned lengthwise within the lower rail member 11, and is slidably mounted in a guideway 29 which is formed in the lower portion of an L-shaped corner reinforcing member 30. The bolt is provided at one end thereof with a tapered nose 31 which projects through an aperture 32 in the stile of the sash, and a solid block 33 is positioned between the sides of the corner reinforcing member 30 at a point just above but in contact with the upper surface of the bolt, whereby to prevent the nose of the same from yielding upwardly when it comes into engagement suddenly and forcibly with a stop during downward movement 100 105 110

of the sash. The corner reinforcing member 30, which is in the form of two laterally spaced and connected L-shaped plates, is positioned in the stile member in closely fitting engagement with the sides thereof by means of a two-part telescoping screw 34, which screw passes through the sides of the stile and reinforcing members at a point where it is in contact with the upper edge 10 of the block 33. The member 30 is positioned in the rail member in similar engagement therewith by means of another two-part telescoping screw 35, which screw passes through not only the sides of the rail 15 and reinforcing members but also through the lock housing 19. The lock housing 19 is secured against the side of the sash by means of the screw 35 already described and two other screws 36 and 37 which pass 20 from the housing into the nearer sides only of the stile and rail members.

The spring 23 in the housing 19 normally holds the finger piece 21 in an elevated position wherein the nose 31 of the bolt 28 is as 25 a consequence held in a projected position for engagement with a stop presented by a suitable lock rack. The movement of the bolt outwardly is limited by a shoulder 38 on the same which abuts against one corner 30 of the block 33. While many different forms of combined sash guides and lock racks may be used in association with the particular form of sash and lock herein disclosed, a very simple and efficient form of 35 combined guide and rack is shown in the drawings. It consists of a channel strip 39, to the back of which is attached, by riveting or welding, a number of sheet metal stampings 40, which stampings are bent to form horizontal stops 41 and inclined side-walls 42 for the stops. When the sash is being raised, the nose 31 of the bolt at each side of the sash will be cammed inwardly as it 40 passes upwardly along the inclined side-walls 42 of the stampings 39, and, when the sash has reached the desired elevation and is being lowered a little to lock, the nose 31 will engage with one of the stops 41 and will hold the sash in that position until the 45 finger piece 21 is depressed.

The improvements in lock construction herein disclosed form part of the subject matter of my co-pending application Serial No. 174,510, filed March 11, 1927 and are 50 therein claimed.

By the use of the term "nested" in describing the arrangement of the two channel members in the following claims, an arrangement is meant wherein one of the channel members is seated within the other with the channels in such members opening in substantially the same as distinguished from opposite directions.

I claim:

1. In a sheet metal sash, a hollow margin-

al member consisting of two channel strips which are arranged together in nested relation with the edges of the inner strip bent reversely about the edges of the outer strip.

2. In a sheet metal sash, a hollow marginal member consisting of a deep U-shaped channel strip, and a shallow U-shaped channel strip contained within the deep strip, the channels in the strips being open in the same direction, the backs of the strips being spaced apart, the sides thereof being in contact with each other, and the edges of the shallow strip being bent reversely about the edges of the deep strip.

3. In a sheet metal sash, a hollow marginal member having a longitudinally extending passageway therein a longitudinally movable locking bolt slidably positioned in the passageway, a lock housing secured against one side of the member, and a movable finger piece carried by the housing and connected with the bolt for reciprocating the same.

4. In a sheet metal sash, a hollow marginal member consisting of two channel strips which are arranged together in such a way as to provide therebetween a longitudinally extending passageway, a longitudinally movable locking bolt slidably positioned in the passageway, a lock housing secured against one side of the member, and a finger piece pivoted within the housing and connected through an opening in the side of the member with the bolt for reciprocating the same.

5. In a sheet metal sash, two hollow marginal members which are arranged to form a sash corner, each of the members consisting of two channel strips which are arranged to form therebetween a longitudinally extending passageway, an L-shaped reinforcing member contained partly within the passageway in one of the sash members and partly within that in the other, a longitudinally movable locking bolt slidably supported by and within that portion of the reinforcing member within the passageway in one of the sash members, and means for reciprocating the bolt.

6. In a sheet metal sash, two hollow marginal members which are arranged to form a sash corner, each of the members consisting of two channel strips which are arranged to form therebetween a longitudinally extending passageway, an L-shaped reinforcing member contained partly within the passageway, in one of the sash members and partly within that in the other, a longitudinally movable locking bolt slidably supported by and within that portion of the reinforcing member within the passageway in one of the sash members, and means positioned exteriorly of the sash members for reciprocating the bolt in the same.

7. In a sheet metal sash, a hollow margin-

al member consisting of a deep channel strip having substantially parallel sides, and a shallow channel strip contained within the deep strip and likewise having substantially parallel sides, the channels in the strips being open in the same direction, the backs of the strips being spaced apart, and the sides of the strips being in contiguous contact with each other and secured together,

whereby to suspend the weight of a sash ¹⁰ pane seated in the channel in the shallow strip in a sling-like construction which is supported solely by those portions of the sides of the deep strip beyond the bottom of the shallow strip.

In testimony whereof I have hereunto subscribed my name. JOHN F. LEVAN.
